FIG. 1

FIG. 2

FIG. 3

FIG. 4

FIG. 5

FIG. 6

AEROSOL GENERATING DEVICE AND OPERATION METHOD THEREOF

TECHNICAL FIELD

One or more embodiments relate to an aerosol generating device and an operation method thereof.

BACKGROUND ART

Recently, the demand for alternatives to traditional cigarettes has increased. For example, there is growing demand for an aerosol generating device that generates an aerosol by heating an aerosol generating material or an aerosol generating article (e.g., a cigarette containing an aerosol generating material), without combusting traditional cigarettes.

An aerosol generating device may include a heater for heating a cigarette or an aerosol generating material. Therefore, there is a need for a technology for preventing heating of an unintended portion of the aerosol generating device and minimizing unnecessary power loss while providing an optimal smoking experience to a user.

DISCLOSURE

Technical Solution

One or more embodiments include an aerosol generating device and an operation method thereof. For example, the aerosol generating device may include a heater including a first electrically conductive track and a second electrically conductive track having a higher temperature coefficient of resistance than the first electrically conductive track, heat a cigarette accommodated in the aerosol generating device by using the first electrically conductive track in a first temperature change section, and heat the cigarette by using the second electrically conductive track in a second temperature change section. The technical problems to be achieved by the present disclosure are not limited to the technical problems as described above, and other technical problems may be inferred from the following embodiments.

Advantageous Effects

The aerosol generating device according to one or more embodiments may heat the cigarette accommodated in the aerosol generating device by using the first electrically conductive track having a low temperature coefficient of resistance in the preheating section, thereby increasing a current flowing through the heater fast. Accordingly, a time needed for preheating may be minimized. The aerosol generating device according to one or more embodiments may heat the cigarette by using the second electrically conductive track having a high temperature coefficient of resistance in a smoking section, thereby reducing a current flowing through the entire circuit including the heater. Therefore, heating of an unintended portion of the aerosol generating device may be prevented, and unnecessary power loss may be minimized.

DESCRIPTION OF DRAWINGS

FIG. 1 is a diagram illustrating an aerosol generating device according to an embodiment.

FIG. 2 shows a cigarette containing an aerosol generating material as an example of an aerosol generating article.

FIG. 3 is a block diagram illustrating a configuration of an aerosol generating device according to an embodiment.

FIG. 4 is a graph illustrating an example of a temperature profile of an aerosol generating device, according to an embodiment.

FIG. 5 is a view illustrating components of an aerosol generating device according to an embodiment.

FIG. 6 is a flowchart illustrating a method of operating an aerosol generating device, according to an embodiment.

10

BEST MODE

According to one or more embodiments, an aerosol generating device includes: a heater including a first electrically conductive track and a second electrically conductive track having a higher temperature coefficient of resistance than the first electrically conductive track; and a controller configured to heat a cigarette accommodated in the aerosol generating device by using the first electrically conductive track in a first temperature change section and heat the cigarette by using the second electrically conductive track in a second temperature change section.

The first temperature change section may correspond to a preheating section for increasing a temperature of the heater up to an operation temperature, and the second temperature change section may correspond to a smoking section for substantially maintaining the temperature of the heater at the operation temperature.

A rate of change in the temperature of the heater over time may be greater than or equal to 8° C./s in the first temperature change section and less than 8° C./s in the second temperature change section.

The aerosol generating device may further include a battery supplying power to the heater, wherein the controller is further configured to control the battery to supply power to the first electrically conductive track in the first temperature change section, and control the battery to supply power to the second electrically conductive track in the second temperature change section.

The aerosol generating device may further include at least one switch configured to select between electrical connection between the battery and the first electrically conductive track and electrical connection of the battery and the second electrically conductive track, wherein the controller is further configured to control the at least one switch such that the battery supplies power to the first electrically conductive track in the first temperature change section and supplies power to the second electrically conductive track in the second temperature change section.

The controller may detect a resistance value of the second electrically conductive track, determine a temperature of the heater based on the detected resistance value and a temperature coefficient of resistance of the second electrically conductive track, and identify the first temperature change section and the second temperature change section based on the determined temperature.

A temperature coefficient of resistance of the first electrically conductive track may be less than 1,800 ppm/° C. in the first temperature change section, and a temperature coefficient of resistance of the second electrically conductive track may be greater than or equal to 2,500 ppm/° C. and less than 4,500 ppm/° C. in the first temperature change section.

According to one or more embodiments, a method of operating an aerosol generating device, includes: heating a cigarette accommodated in the aerosol generating device by using a first electrically conductive track in a first temperature change section; and heating the cigarette by using a

second electrically conductive track having a higher temperature coefficient of resistance than the first electrically conductive track in a second temperature change section.

A computer-readable recording medium according to one or more embodiments includes a recording medium on which one or more programs including instructions for executing the above-described method have been recorded.

MODE FOR INVENTION

With respect to the terms used to describe the various embodiments, general terms which are currently and widely used are selected in consideration of functions of structural elements in the various embodiments of the present disclosure. However, meanings of the terms can be changed according to intention, a judicial precedence, the appearance of new technology, and the like. In addition, in certain cases, a term which is not commonly used can be selected. In such a case, the meaning of the term will be described in detail at the corresponding portion in the description of the present disclosure. Therefore, the terms used in the various embodiments of the present disclosure should be defined based on the meanings of the terms and the descriptions provided herein.

In addition, unless explicitly described to the contrary, the word "comprise" and variations such as "comprises" or "comprising" will be understood to imply the inclusion of stated elements but not the exclusion of any other elements. In addition, the terms "-er", "-or", and "module" described in the specification mean units for processing at least one function and operation and can be implemented by hardware components or software components and combinations thereof.

As used herein, expressions such as "at least one of," when preceding a list of elements, modify the entire list of elements and do not modify the individual elements of the list. For example, the expression, "at least one of a, b, and c," should be understood as including only a, only b, only c, both a and b, both a and c, both b and c, or all of a, b, and c.

It will be understood that when an element or layer is referred to as being "over," "above," "on," "connected to" or "coupled to" another element or layer, it can be directly over, above, on, connected or coupled to the other element or layer or intervening elements or layers may be present. In contrast, when an element is referred to as being "directly over," "directly above," "directly on," "directly connected to" or "directly coupled to" another element or layer, there are no intervening elements or layers present. Like numerals refer to like elements throughout.

Hereinafter, the present disclosure will now be described more fully with reference to the accompanying drawings, in which exemplary embodiments of the present disclosure are shown such that one of ordinary skill in the art may easily work the present disclosure. The disclosure may, however, be embodied in many different forms and should not be construed as being limited to the embodiments set forth herein.

Hereinafter, embodiments of the present disclosure will be described in detail with reference to the drawings.

FIG. 1 is a diagram illustrating an aerosol generating device according to an embodiment.

Referring to FIG. 1, the aerosol generating device 10000 may include a battery 11000, a controller 12000, and a heater 13000. Also, an aerosol generating article 20000 (e.g., a cigarette) may be inserted into an inner space of the aerosol generating device 10000.

FIG. 1 shows the aerosol generating device 10000 with some elements related to the embodiment. Therefore, it will be understood by one of ordinary skill in the art related to the present embodiment that other general-purpose components 5 may be further included in the aerosol generating device 10000, in addition to the components illustrated in FIG. 1.

FIG. 1 illustrates that the battery 11000, the controller 12000, and the heater 13000 are arranged in series, but the arrangement of these are not limited thereto. In other words, 10 according to the design of the aerosol generating device 10000, the arrangement of the battery 11000, the controller 12000, and the heater 13000 may be modified.

When the cigarette 20000 is inserted into the aerosol generating device 10000, the aerosol generating device 15 10000 heats the heater 13000. The temperature of an aerosol generating material in the cigarette 20000 is raised by the heated heater 13000, and thus aerosol is generated. The generated aerosol is delivered to a user through a second portion 22000 of the cigarette 20000.

According to necessity, even when the cigarette 20000 is not inserted into the aerosol generating device 10000, the aerosol generating device 10000 may heat the heater 13000.

The battery 11000 supplies electric power to be used for 20 the aerosol generating device 10000 to operate. For example, the battery 11000 may supply power for heating the heater 13000 and supply power for operating the controller 12000. Also, the battery 11000 may supply power for operations of a display, a sensor, a motor, etc. mounted in the 25 aerosol generating device 10000.

The controller 12000 may generally control operations of the aerosol generating device 10000. In detail, the controller 12000 controls not only operations of the battery 11000 and the heater, but also operations of other components included 30 in the aerosol generating device 10000. Also, the controller 12000 may check a state of each of the components of the aerosol generating device 10000 to determine whether or not the aerosol generating device 10000 is able to operate.

The controller 12000 may include at least one processor. 35 40 A processor can be implemented as an array of a plurality of logic gates or can be implemented as a combination of a general-purpose microprocessor and a memory in which a program executable in the microprocessor is stored. It will be understood by one of ordinary skill in the art that the processor can be implemented in other forms of hardware.

The heater 13000 is heated by power supplied from the battery 11000. For example, when the cigarette 20000 is inserted into the aerosol generating device 10000, the heater 13000 may be located inside the cigarette 20000. Thus, the 45 heated heater 13000 may increase a temperature of an aerosol generating material in the cigarette 20000.

The heater 13000 may include an electro-resistive heater. For example, the heater 13000 may include an electrically 50 55 conductive track, and the heater 13000 may be heated when currents flow through the electrically conductive track. However, the heater 13000 is not limited to the example described above and may include all heaters which may be heated to a desired temperature. Here, the desired temperature may be pre-set in the aerosol generating device 10000 or may be set as a temperature desired by a user.

FIG. 1 illustrates that the heater 13000 is inserted into the cigarette 20000, but the position of the heater 13000 is not limited thereto. For example, the heater 13000 may include a tube-type heating element, a plate-type heating element, a 60 65 needle-type heating element, or a rod-type heating element, and may heat the inside or the outside of the cigarette 20000, according to the shape of the heating element.

Also, the aerosol generating device **10000** may include a plurality of heaters **13000**. Here, the plurality of heaters **13000** may be inserted into the cigarette **20000** or may be arranged outside the cigarette **20000**. Also, some of the plurality of heaters **13000** may be inserted into the cigarette **20000** and the others may be arranged outside the cigarette **20000**. In addition, the shape of the heater **13000** is not limited to the shape illustrated in FIG. 1, and may include various shapes.

The aerosol generating device **10000** may further include general-purpose components in addition to the battery **11000**, the controller **12000**, and the heater **13000**. For example, the aerosol generating device **10000** may include a display capable of outputting visual information and/or a motor for outputting haptic information. Also, the aerosol generating device **10000** may include at least one sensor (e.g., a puff detecting sensor, a temperature detecting sensor, a cigarette insertion detecting sensor, etc.).

Also, the aerosol generating device **10000** may be formed as a structure where, even when the cigarette **20000** is inserted into the aerosol generating device **10000**, external air may be introduced or internal air may be discharged.

Although not illustrated in FIG. 1, the aerosol generating device **10000** and an additional cradle may form together a system. For example, the cradle may be used to charge the battery **11000** of the aerosol generating device **10000**. Alternatively, the heater **13000** may be heated when the cradle and the aerosol generating device **10000** are coupled to each other.

The cigarette **20000** may be similar as a general combustive cigarette. For example, the cigarette **20000** may be divided into a first portion **21000** including an aerosol generating material and a second portion **22000** including a filter or the like. Alternatively, the second portion **22000** of the cigarette **20000** may also include an aerosol generating material. For example, an aerosol generating material made in the form of granules or capsules may be inserted into the second portion **22000**.

The first portion **21000** may be completely inserted into the aerosol generating device **10000**, and the second portion **22000** may be exposed to the outside. In some embodiments, only a portion of the first portion **21000** may be inserted into the aerosol generating device **10000**, or a portion of the first portion **21000** and a portion of the second portion **22000** may be inserted thereinto. The user may puff aerosol while holding the second portion **22000** by the mouth of the user. In this case, the aerosol is generated by the external air passing through the first portion **21000**, and the generated aerosol passes through the second portion **22000** and is delivered to the user's mouth.

For example, the external air may flow into at least one air passage formed in the aerosol generating device **10000**. For example, the opening and closing and/or a size of the air passage formed in the aerosol generating device **10000** may be adjusted by the user. Accordingly, the amount of smoke and a smoking impression may be adjusted by the user. As another example, the external air may flow into the cigarette **20000** through at least one hole formed in a surface of the cigarette **20000**.

Hereinafter, an example of the cigarette **20000** will be described with reference to FIG. 2.

FIG. 2 shows a view showing a cigarette containing an aerosol generating material as an example of an aerosol generating article.

Referring to FIG. 2, the cigarette **20000** includes a tobacco rod **21000** and a filter rod **22000**. The first portion

21000 described above with reference to FIG. 1 includes the tobacco rod **21000**, and the second portion **22000** includes the filter rod **22000**.

The filter rod **22000** illustrated in FIG. 2 is illustrated as a single segment, but is not limited thereto. In other words, the filter rod **22000** may include a plurality of segments. For example, the filter rod **22000** may include a first segment configured to cool an aerosol and a second segment configured to filter a certain component included in the aerosol.

10 Also, according to necessity, the filter rod **22000** may further include at least one segment configured to perform other functions.

The cigarette **20000** may be packaged by at least one wrapper **24000**. The wrapper **24000** may have at least one hole through which external air may be introduced or internal air may be discharged. For example, the cigarette **20000** may be packaged by one wrapper **24000**. As another example, the cigarette **20000** may be double-packaged by at least two wrappers **24000**. For example, the tobacco rod **21000** may be packaged by a first wrapper, and the filter rod **22000** may be packaged by a second wrapper. Also, the tobacco rod **21000** and the filter rod **22000**, which are respectively packaged by separate wrappers, may be coupled to each other, and the entire cigarette **20000** may be packaged by a third wrapper. When each of the tobacco rod **21000** and the filter rod **22000** includes a plurality of segments, each segment may be packaged by a separate wrapper. Also, the entire cigarette **20000** including the plurality of segments, which are respectively packaged by the separate wrappers and which are coupled to each other, may be re-packaged by another wrapper.

The tobacco rod **21000** may include an aerosol generating material. For example, the aerosol generating material may include at least one of glycerin, propylene glycol, ethylene glycol, dipropylene glycol, diethylene glycol, triethylene glycol, tetraethylene glycol, and oleyl alcohol, but it is not limited thereto. Also, the tobacco rod **21000** may include other additives, such as flavors, a wetting agent, and/or organic acid. Also, the tobacco rod **21000** may include a flavored liquid, such as menthol or a moisturizer, which is injected to the tobacco rod **21000**.

The tobacco rod **21000** may be manufactured in various forms. For example, the tobacco rod **21000** may be formed as a sheet or a strand. Also, the tobacco rod **21000** may be formed as a pipe tobacco, which is formed of tiny bits cut from a tobacco sheet. Also, the tobacco rod **21000** may be surrounded by a heat conductive material. For example, the heat conductive material may be, but is not limited to, a metal foil such as aluminum foil. For example, the heat conductive material surrounding the tobacco rod **21000** may uniformly distribute heat transmitted to the tobacco rod **21000**, and thus, the heat conductivity applied to the tobacco rod may be increased and taste of the tobacco may be improved.

55 The filter rod **22000** may include a cellulose acetate filter. Shapes of the filter rod **22000** are not limited. For example, the filter rod **22000** may include a cylinder-type rod or a tube-type rod having a hollow inside. Also, the filter rod **22000** may include a recess-type rod. When the filter rod **22000** includes a plurality of segments, at least one of the plurality of segments may have a different shape.

60 The filter rod **22000** may be formed to generate flavors. For example, a flavoring liquid may be injected onto the filter rod **22000**, or an additional fiber coated with a flavoring liquid may be inserted into the filter rod **22000**.

Also, the filter rod **22000** may include at least one capsule **23000**. Here, the capsule **23000** may generate a flavor or an

aerosol. For example, the capsule **23000** may have a configuration in which a liquid containing a flavoring material is wrapped with a film. For example, the capsule **23000** may have a spherical or cylindrical shape, but is not limited thereto.

When the filter rod **22000** includes a segment configured to cool the aerosol, the cooling segment may include a polymer material or a biodegradable polymer material. For example, the cooling segment may include pure polylactic acid alone, but the material for forming the cooling segment is not limited thereto. In some embodiments, the cooling segment may include a cellulose acetate filter having a plurality of holes. However, the cooling segment is not limited to the above-described example and is not limited as long as the cooling segment cools the aerosol.

FIG. 3 is a block diagram illustrating a configuration of an aerosol generating device according to an embodiment.

Referring to FIG. 3, an aerosol generating device **10000** may include a controller **12000** and a heater **13000**. The controller **12000** and the heater **13000** of FIG. 3 correspond to the controller **12000** and the heater **13000** of FIG. 1, respectively, and thus, repeated descriptions thereof will be omitted herein. The aerosol generating device **10000** illustrated in FIG. 3 illustrates components related to the present embodiment. Therefore, it will be understood by one of ordinary skill in the art related to the present embodiment that other components may be further included in the aerosol generating device **10000**, in addition to the components illustrated in FIG. 3.

The heater **13000** included in the aerosol generating device **10000** may include a first electrically conductive track **310** and a second electrically conductive track **320**. The second electrically conductive track **320** may have a higher temperature coefficient of resistance than the first electrically conductive track **310**. A temperature coefficient of resistance refers to a rate at which a resistance value changes according to a temperature. As a temperature coefficient of resistance increases, a change in a resistance value according to a change in temperature becomes greater. As the temperature coefficient of resistance decreases, the change in the resistance value according to the change in the temperature becomes smaller. In general, because a metal has a positive temperature coefficient of resistance, a resistance value increases according to an increase in temperature.

In an example, the first electrically conductive track **310** and the second electrically conductive track **320** may be made of a material including at least one of tungsten, platinum, and molybdenum. However, the first electrically conductive track **310** and the second electrically conductive track **320** are not limited thereto. As long as the second electrically conductive track **320** has a higher temperature coefficient of resistance than the first electrically conductive track **310**, each of the first electrically conductive track **310** and the second electrically conductive track **320** may be made of any suitable material. A temperature coefficient of resistance of the first electrically conductive track **310** may be less than 1,800 ppm/ $^{\circ}$ C. when a temperature is about 25 $^{\circ}$ C. to about 360 $^{\circ}$ C., and a temperature coefficient of resistance of the second electrically conductive track **320** may be higher than or equal to 2,500 ppm/ $^{\circ}$ C. when a temperature is about 25 $^{\circ}$ C. to about 360 $^{\circ}$ C.

The controller **12000** may heat a cigarette accommodated in the aerosol generating device **10000** by using the first electrically conductive track **310** in a first temperature change section, and heat the cigarette by using the second electrically conductive track **320** in a second temperature

change section. The first temperature change section may correspond to a preheating section for increasing a temperature of the heater **13000** up to an operation temperature, and the second temperature change section may correspond to a smoking section for substantially maintaining the temperature of the heater **13000** at the operation temperature. Here, the operation temperature may refer to a temperature that is sufficiently high to generate an aerosol from an aerosol generating material included in the cigarette **20000**. For example, the operation temperature may be about 200 $^{\circ}$ C. to about 400 $^{\circ}$ C., and may preferably be about 250 $^{\circ}$ C. to about 330 $^{\circ}$ C. However, the operation temperature is not limited thereto. Hereinafter, the first temperature change section and the second temperature change section will be described in more detail with reference to FIG. 4.

FIG. 4 is a graph illustrating an example of a temperature profile of an aerosol generating device, according to an embodiment.

FIG. 4 illustrates an example of a temperature profile for generating an aerosol by heating a cigarette by an aerosol generating device. The aerosol generating device may perform preheating so that a sufficient aerosol may be generated from a cigarette before a user smokes using the aerosol generating device. For example, as shown in FIG. 4, the aerosol generating device may increase a temperature of a heater from room temperature (i.e., about 25 $^{\circ}$ C.) to about 330 $^{\circ}$ C. in about 30 seconds, so that the user may inhale an aerosol at any time when puffing. As described above, a preheating section in which a temperature is rapidly increased within a relatively short time may correspond to a first temperature change section. In an example, a rate of change in temperature of the heater may be greater than or equal to 8 $^{\circ}$ C./s in the first temperature change section.

After the aerosol generating device finishes preheating, the aerosol generating device may substantially maintain the temperature of the heater at an operation temperature so that the user may smoke using the aerosol generating device. For example, the aerosol generating device may maintain the temperature of the heater at about 330 $^{\circ}$ C. during a smoking section. As such, a smoking section in which a change in temperature is relatively small may correspond to a second temperature change section. In an example, a rate of change in the temperature of the heater may be less than 8 $^{\circ}$ C./s in the second temperature change section.

The temperature profile illustrated in FIG. 4 is merely an example, and the aerosol generating device may heat the cigarette according to other temperature profiles. For example, the temperature of the heater may be higher or lower than 330 $^{\circ}$ C. at a point in time when preheating of the aerosol generating device is completed.

According to embodiments, the aerosol generating device may not maintain the temperature of the heater constant in the smoking section but appropriately change the temperature of the heater based on the number of puffs by the user. Even in this case, as long as the rate of the change in the temperature of the heater over time is relatively small (e.g., less than 8 $^{\circ}$ C./s) in the smoking section, the smoking section may correspond to the second temperature change section.

Referring to FIG. 3 again, the temperature coefficient of resistance of the first electrically conductive track **310** may be less than 1,800 ppm/ $^{\circ}$ C. in the first temperature change section, and the temperature coefficient of resistance of the second electrically conductive track **320** may be higher than or equal to 2,500 ppm/ $^{\circ}$ C. in the first temperature change section. Also, an initial resistance value (i.e., a resistance value at room temperature) of the first electrically conductive track **310** may be less than 1,800 ppm/ $^{\circ}$ C. in the first temperature change section, and the initial resistance value of the second electrically conductive track **320** may be higher than or equal to 2,500 ppm/ $^{\circ}$ C. in the first temperature change section.

tive track **310** may be less than an initial resistance value of the second electrically conductive track **320**.

As described above, the controller **12000** may heat the cigarette accommodated in the aerosol generating device **10000** by using the first electrically conductive track **310** having a low temperature coefficient of resistance in a preheating section, thereby increasing a current flowing through the heater **13000**. As the first electrically conductive track **310** having the low temperature coefficient of resistance has a lower resistance value than the second electrically conductive track **320**, a current flowing through the heater **13000** may be greater when the cigarette is heated by using the first electrically conductive track **310** than when the cigarette is heated by using the second electrically conductive track **320**. As the current flowing through the heater **13000** increases, an amount of heat generated from the heater **13000** may increase, and a time needed for preheating may be reduced.

The controller **12000** may heat the cigarette by using the second electrically conductive track **320** having a high temperature coefficient of resistance in a temperature maintenance section (i.e., second temperature change section), thereby reducing a current flowing through the entire circuit including the heater **13000**. As the second electrically conductive track **320** has the high temperature coefficient of resistance, its resistance value significantly increases during the preheating section, and thus has a higher resistance value than the first electrically conductive track **310** in the temperature maintenance section. Therefore, when the cigarette is heated by using the second electrically conductive track **320** in the temperature maintenance section, a current flowing through the entire circuit including the heater **13000** is reduced. Therefore, heating of an unintended portion of the aerosol generating device may be prevented, and unnecessary power loss may be minimized. Hereinafter, the strong points of heating a cigarette by using the second electrically conductive track **320** in the second temperature change section will be described in more detail with reference to FIG. 5.

FIG. 5 is a view illustrating components of an aerosol generating device, according to an embodiment.

FIG. 5 illustrates an example in which a battery **11000** supplies power to a first electrically conductive track **310** or a second electrically conductive track **320** included in a heater.

A controller (e.g., the controller **12000** of FIGS. 1 and 3) may control the battery **11000** to supply power to the first electrically conductive track **310** in a first temperature change section and control the battery **11000** to supply power to the second electrically conductive track **320** in a second temperature change section. An aerosol generating device may further include at least one switch for selecting between electrical connection of the battery **11000** and the first electrically conductive track **310** and electrical connection of the battery **11000** and the second electrically conductive track **320**. For example, as illustrated in FIG. 5, the aerosol generating device may include an on/off switch **510**.

By using the on/off switch **510**, the controller may control the battery **11000** to supply power to the first electrically conductive track **310** in the first temperature change section and control the battery **11000** to supply power to the second electrically conductive track **320** in the second temperature change section.

The controller may detect a resistance value of the second electrically conductive track **320** and determine a temperature of the heater based on the detected resistance value and a temperature coefficient of resistance of the second elec-

trically conductive track **320**. As the second electrically conductive track **320** has a high temperature coefficient of resistance, a change in a resistance value according to a change in temperature may be great. Therefore, a change in the temperature of the heater may be finely reflected in a resistance value of the second electrically conductive track **320**. In this regard, when the second electrically conductive track **320** is used, the temperature of the heater may be accurately detected.

In an example, the controller may use a temperature sensing circuit **520** electrically connected to the second electrically conductive track **320** to detect a resistance value of the second electrically conductive track **320**, and determine a temperature of the heater based on the detected resistance value and a temperature coefficient of resistance of the second electrically conductive track **320**. FIG. 5 illustrates that the temperature sensing circuit **520** is connected in series to the second electrically conductive track **320**, but the temperature sensing circuit **520** is not limited thereto. The temperature sensing circuit **520** may be connected in parallel to the second electrically conductive track **320**.

The controller may identify the first temperature change section and the second temperature change section based on the determined temperature. In an example, the controller may determine that the heater is operating in the first temperature change section when the determined temperature is less than a preset threshold, and determine that the heater is operating in the second temperature change section when the determined temperature is greater than or equal to the preset threshold. However, the controller is not limited thereto, and may calculate a rate of change in temperature over time based on the determined temperature and determine whether the heater is operating in the first temperature change section or the second temperature change section based on the calculated rate of the change in the temperature over time.

In an example, the aerosol generating device may further include a current control switch **530** for controlling a current flowing through a circuit formed inside the aerosol generating device not to exceed a preset limit. As described above, the circuit formed inside the aerosol generating device may further include additional circuit configurations such as the on/off switch **510**, the temperature sensing circuit **520**, and the current control switch **530**, in addition to the battery **11000**, the first electrically conductive track **310**, and the second electrically conductive track **320**. Also, parasitic resistance may exist in lines connecting the circuit configurations. Therefore, when a current flowing along the circuit formed inside the aerosol generating device is overly increased, heating of an unintended portion of the aerosol generating device may be prevented, and unnecessary power loss may occur.

The aerosol generating device **10000** according to the present disclosure may reduce a current flowing through the entire circuit including a heater by heating a cigarette with the second electrically conductive track **320** having a high temperature coefficient of resistance during a second temperature change section, thereby preventing heating of an unintended portion and minimizing unnecessary power loss.

FIG. 6 is a flowchart illustrating a method of operating an aerosol generating device according to an embodiment.

Referring to FIG. 6, the method of operation of the aerosol generating device include operations that are processed in the aerosol generating device **10000** illustrated in FIGS. 1 and 3. Therefore, even if omitted below, the description of the aerosol generating device **10000** illustrated in FIGS. 1

11

and 3 may also be applied to the method of operation of the aerosol generating device shown in FIG. 6.

In operation 610, the aerosol generating device may heat a cigarette accommodated in the aerosol generating device by using a first electrically conductive track in a first temperature change section. The aerosol generating device may perform preheating so that sufficient aerosol is generated from the cigarette before a user smokes by using the aerosol generating device. The first temperature change section may correspond to a preheating section for increasing a temperature of a heater up to an operation temperature. As aforementioned, the temperature may be changed rapidly within a relatively short time during the first temperature change section. For example, a rate of change in temperature of the heater over time may be greater than or equal to 8° C/s in the first temperature change section. A temperature coefficient of resistance of the first electrically conductive track may be less than 1,800 ppm/° C. in the first temperature change section, but is not limited thereto.

The aerosol generating device may control a battery to supply power to the first electrically conductive track in the first temperature change section. For example, the aerosol generating device may control the battery to supply power to the first electrically conductive track in the first temperature change section by using at least one switch for selecting between electrical connection of the battery and the first electrically conductive track and electrical connection of the battery and a second electrically conductive track.

In operation 620, the aerosol generating device may heat the cigarette by using the second electrically conductive track having a higher temperature coefficient of resistance than the first electrically conductive track in a second temperature change section. The aerosol generating device may substantially maintain the temperature of the heater at the operation temperature after preheating is completed so that the user may smoke by using the aerosol generating device. The second temperature change section may correspond to a smoking section in which the temperature of the heater is substantially maintained at the operation temperature. As aforementioned, a change in temperature is relatively small in the second temperature change section. For example, a rate of change in the temperature of the heater over time may be less than 8° C/s in the second temperature change section. A temperature coefficient of resistance of the second electrically conductive track may be greater than or equal to 2,500 ppm/° C. in the first temperature change section, but is not limited thereto.

The aerosol generating device may control the battery to supply power to the second electrically conductive track in the second temperature change section. For example, the aerosol generating device may control the battery to supply power to the second electrically conductive track in the second temperature change section by using at least one switch for selecting between electrical connection of the battery and the first electrically conductive track and electrical connection of the battery and the second electrically conductive track.

The aerosol generating device may detect a resistance value of the second electrically conductive track, determine the temperature of the heater based on the detected resistance value and the temperature coefficient of resistance of the second electrically conductive track, and identify the first temperature change section and the second temperature change section based on the determined temperature. In an example, the aerosol generating device may determine that the heater is operating in the first temperature change section if the determined temperature is less than a preset threshold,

12

and determine that the heater is operating in the second temperature change section if the determined temperature is greater than or equal to the preset threshold. However, the aerosol generating device is not limited thereto. For example, the aerosol generating device may calculate a rate of change in temperature over time based on the determined temperature, and identify the first temperature change section and the second temperature change section based on the calculated rate of the change in temperature over time.

The method illustrated in FIG. 6 may be recorded on a computer-readable recording medium in the form of one or more programs including instructions for executing the method have been recorded. Examples of the computer-readable recording medium may include magnetic media such as a hard disk, a floppy disk, and a magnetic tape, optical media such as CD-ROM and DVD, magneto-optical media such as a floptical disk, and a hardware device specifically configured to store and perform a program instruction such as ROM, RAM, flash memory, or the like. Examples of the program instruction include high-level language code executable by a computer by using an interpreter or the like, as well as machine language code made by compiler.

At least one of the components, elements, modules or units (collectively "components" in this paragraph) represented by a block in the drawings, such as the controller 12000 in FIGS. 1 and 3, may be embodied as various numbers of hardware, software and/or firmware structures that execute respective functions described above, according to an exemplary embodiment. For example, at least one of these components may use a direct circuit structure, such as a memory, a processor, a logic circuit, a look-up table, etc. that may execute the respective functions through controls of one or more microprocessors or other control apparatuses. Also, at least one of these components may be specifically embodied by a module, a program, or a part of code, which contains one or more executable instructions for performing specified logic functions, and executed by one or more microprocessors or other control apparatuses. Further, at least one of these components may include or may be implemented by a processor such as a central processing unit (CPU) that performs the respective functions, a microprocessor, or the like. Two or more of these components may be combined into one single component which performs all operations or functions of the combined two or more components. Also, at least part of functions of at least one of these components may be performed by another of these components. Further, although a bus is not illustrated in the above block diagrams, communication between the components may be performed through the bus. Functional aspects of the above exemplary embodiments may be implemented in algorithms that execute on one or more processors. Furthermore, the components represented by a block or processing steps may employ any number of related art techniques for electronics configuration, signal processing and/or control, data processing and the like.

Those of ordinary skill in the art related to the present embodiments may understand that various changes in form and details can be made therein without departing from the scope of the characteristics described above. The disclosed methods should be considered in a descriptive sense only and not for purposes of limitation. The scope of the present disclosure is defined by the appended claims rather than by the foregoing description, and all differences within the scope of equivalents thereof should be construed as being included in the present disclosure.

13

What is claimed is:

1. An aerosol generating device comprising:
a heater including a first electrically conductive track and a second electrically conductive track having a higher temperature coefficient of resistance than the first electrically conductive track;
a battery configured to supply power to the heater, and a controller configured to control the battery to selectively supply power to the first electrically conductive track for heating a tobacco rod of a cigarette accommodated in the aerosol generating device in a first temperature change section or supply power to the second electrically conductive track for heating the tobacco rod of the cigarette in a second temperature change section, the cigarette comprising the tobacco rod and a filter rod, wherein the first temperature change section corresponds to a preheating section for increasing a temperature of the heater up to an operation temperature, and the second temperature change section corresponds to a smoking section for substantially maintaining the temperature of the heater at the operation temperature, and wherein the operation temperature is a temperature at which aerosol is generated from an aerosol generating material included in the tobacco rod.

2. The aerosol generating device of claim 1, wherein a rate of change in a temperature of the heater over time is greater than or equal to 8° C./s in the first temperature change section and less than 8° C./s in the second temperature change section.

3. The aerosol generating device of claim 1, further comprising at least one switch configured to select between electrical connection of the battery and the first electrically conductive track and electrical connection of the battery and the second electrically conductive track,

wherein the controller is further configured to control the at least one switch such that the battery supplies power to the first electrically conductive track in the first temperature change section and supplies power to the second electrically conductive track in the second temperature change section.

14

4. The aerosol generating device of claim 1, wherein the controller is further configured to detect a resistance value of the second electrically conductive track, determine the temperature of the heater based on the detected resistance value and a temperature coefficient of resistance of the second electrically conductive track, and identify the first temperature change section and the second temperature change section based on the determined temperature.

5. The aerosol generating device of claim 1, wherein a temperature coefficient of resistance of the first electrically conductive track is less than 1,800 ppm/° C. in the first temperature change section, and a temperature coefficient of resistance of the second electrically conductive track is greater than or equal to 2,500 ppm/° C. in the second temperature change section.

6. A method of operating an aerosol generating device, the method comprising:

controlling a battery to supply power to a first electrically conductive track for heating a tobacco rod of cigarette accommodated in the aerosol generating device in a first temperature change section corresponding to a preheating section for increasing a temperature of the heater up to an operation temperature; and controlling the battery to selectively supply power to a second electrically conductive track having a higher temperature coefficient of resistance than the first electrically conductive track for heating the tobacco rod of the cigarette in a second temperature change section corresponding to a smoking section for substantially maintaining the temperature of the heater at the operation temperature,

wherein the operation temperature is a temperature at which aerosol is generated from an aerosol generating material included in the tobacco rod.

7. A computer-readable recording medium having recorded thereon one or more programs including instructions for executing the method of claim 6.
